ANDREW E. GRISWOLD, OF SEATTLE, WASHINGTON.

SAFETY SWITCH-PANEL.

1,172,019.

Specification of Letters Patent. Patented Feb. 15, 1916.

Application filed January 21, 1915. Serial No. 3,462.

To all whom it may concern:

Be it known that I, ANDREW E. GRISWOLD, a citizen of the United States, and a resident of Seattle, in the county of King and 5 State of Washington, have invented certain new and useful Improvements in Safety Switch-Panels, of which the following is a full, true, and exact specification.

My invention relates to safety switch 10 panels and has for its principal objects; to generally improve a multiple switch panel in such a way as to allow the safety cover to be removed, without in any way affecting the operation or utility of the switches, as 15 is desirable in the removal of any particular switch for repairs or otherwise; to improve safety panel construction in such a way as to render it safer of operation when the safety cover is removed.

Other objects will appear as my invention 20 is more fully explained in the following specification, illustrated in the accompanying drawings and pointed out in the appended claims.

In the drawings, Figure 1 is a plan view 25 of my device with certain parts broken away. Fig. 2 is a longitudinal cross section through Fig. 1 with certain parts removed.

Referring more particularly to the drawings, numeral 1 designates an outer casing having an outer hinged door 2 and an inner door 3 which is set into and hinged to door 2. An insulation base 4 and sides 5 inclose the usual bus bars 6, 7 and 8, having connections 6^a, 7^a and 8^a respectively, branch bars 9, 10 and 11, clips 12, 13, 14, 12^a, 13^a and 14^a, which convey the current to vertical spring contact angles 15. The contact angles are arranged in groups of four and 40 are adapted to receive and frictionally hold inserted between them, a standard push button snap switch 16 having the usual push buttons 17 and 17^a for operating said switch. The clips 12^a, 13^a and 14^a connect to one 45 member 18 of fuse cartridge-holders. Similar cartridge holders 19 are screwed to the base 4 and form terminals for the connections of the usual circuit wires. A fusible cartridge 20 completes the circuit. Four 50 screwed posts 21 are secured to base 4 and support a safety cover 22 which is provided with holes which closely fit about push buttons 17 and 17^a. Safety plate 22 is held in place by cap units 23 on bolts 21. Guard angles 24 secured to the inner side of door 2, fit down close to safety cover 22 in such

a way as to prevent a flash from passing around the edge of safety cover 22. Handles 25 facilitate the removal of safety cover 22. The object of the safety cover is to protect the operator of the switches from coming in contact with any live connections, and, as the push buttons project through the safety cover, it does not interfere with the operation of the switches. In 65 operating the switches, door 3 only is opened.

When it is desired to remove one of the switches 16 from the panel, as is necessary to make repairs, the cap units 23 are removed, door 2 opened and safety cover 22 lifted out by handles 25 without in any way interfering with the operation or utility of the switches. The defective switch is now pulled from between contact angles 15 and 70 repaired and replaced or another one inserted in its place. During this operation, any of the other switches may be operated at any time as usual, without replacing any parts. It will be apparent that this is a 80 marked advantage over the usual practice of removing the handles of snap switches, which are in general use for panels, before being able to remove the safety cover and having to either replace them immediately, 85 at some danger to the operator or leave them off until the safety cover is replaced again. During the time the cover is off, the switches would be inoperative in that the handles 90 would be removed from them.

As it is frequently necessary to operate the switches instantly and without delay, it will be understood to be a serious disadvantage to have said switches partly dismantled or rendered inoperative at any 95 time.

While I have shown a particular form of embodiment of my invention, I am aware that many minor changes therein, will readily suggest themselves to others skilled in 100 the art without departing from the spirit and scope of the invention, and I therefore desire to avoid being limited to the exact form shown and described, except as defined in the appended claims.

Having described my invention, what I claim as new and desire to protect by Letters Patent, is—

1. In an article of the class described, the combination of an outer casing, a system of 110 switches within the casing, the switch operating means being of the push button

type, spring contact members which frictionally hold the said switches bodily in place, whereby said switches are readily removable, a removable safety plate for covering the live electrical connections within the casing, the said plate being positioned above the said switches and supported from the said casing and the said plate being provided with a plurality of openings through which the said push buttons snugly but slidably project, whereby the safety plate may be removed without removing any of the push buttons.

2. In an article of the class described, the combination of an outer casing, an outer door for the casing, a system of switches within the casing, a safety plate for cover-

ing the live electrical connection within the casing, the said plate being provided with a plurality of openings, screw posts which project from the bottom of the outer casing, and holding nuts by means of which the said covering is removably supported, a push button for every switch, the said push buttons projecting above the said safety plate and slidably though snugly fitting the said openings, whereby the safety plate may be removed without removing any of the push buttons.

ANDREW E. GRISWOLD.
